UNITED STATES PATENT OFFICE.

CHARLES L. BASTIAN, OF CHICAGO, ILLINOIS, ASSIGNOR TO BOTTLES MACHINERY
MANUFACTURING COMPANY, OF CHICAGO, ILLINOIS, A CORPORATION OF ILLINOIS.

BOTTLE-FILLING MACHINE.

971,962.

Specification of Letters Patent. Patented Oct. 4, 1910.

Application filed April 23, 1908. Serial No. 313,147.

To all whom it may concern:

Be it known that I, CHARLES L. BASTIAN, a citizen of the United States, residing at Chicago, in the county of Cook and State of Illinois, have invented new and useful Improvements in Bottle-Filling Machines, of which the following is a specification.

The object of this invention is to readily adapt a bottle filling machine to fill different sizes of bottles, such as quarts, pints and splits.

With this object in view the invention consists primarily in providing a supplemental head which can be easily and quickly arranged in place on the filling valve mechanism to adapt the machine for filling bottles of a smaller size.

In the accompanying drawings Figure 1 illustrates a filling valve mechanism embodying my invention. Fig. 2 is a sectional view on the line 2—2 of Fig. 1. Fig. 3 is a detail view of the supplemental head.

Referring to the drawings 5 designates the body of the filling valve mechanism and it is provided with a central bore 6 into which the filling tube 7 is secured. The body may be secured into the bottom of a tank or head of the filling machine (not shown) in any suitable manner and it is provided with a seat 8 at the upper end of the bore 6 to receive a liquid valve 9 which is carried by a cross piece 10. Rods 11 are slidably arranged in the body 5 and carry the cross piece. Springs 12 are held in place on the rods below the body by adjustable nuts 13 or other suitable devices and the tension of the springs is exerted to normally hold the liquid valve against its seat. A head 14 is slidably arranged on the filling tube and on the lower ends of the rods 11. This head is provided with a seat 15 on its lower face for the mouth of the bottle and it has an enlarged bore 16 which communicates by a lateral passage 17 with a chamber 18. An air tube 19 is screwed into a nipple 20 which in turn is screwed into the upper end of the chamber 18, and the upper end of this air tube projects through the body of the valve and carries an air valve 21 which has a seat 22 on said body. This air valve is inclosed within an elongated tubular housing 23 which is secured in upright position to the body over the air valve and a spring 24 inclosed within this housing constantly bears on the air valve

to assist the springs 12 in returning the movable parts to their normal position. An extension of the housing in the form of a tube 25 carries the air discharge above the level of the liquid in the tank. The valve mechanism as thus described may be constructed and arranged and adapted for filling quart bottles and in order to change rapidly to fill pints I provide a supplemental head 14' which has a seat 15' to accommodate the mouth of the bottle. The supplemental head has a bore 16' to receive the filling tube and this bore may be enlarged like the bore 16 in the head 14 or grooves 26 may be provided to permit free passage of air between the tank and the bottle. The supplemental head is adapted to be secured to the main head 14 by spring clamping arms 27 which are fastened to the head and are provided with shoulders 28 to engage the top of the main head. The upper ends 29 of these arms, above the shoulders, are flared outwardly so that the arms can be readily disengaged from the main head to permit the removal of the supplemental head.

In applying the supplemental head to the valve mechanism it is pushed up on the filling tube until the outwardly flared ends of the arms engage the bottom of the main head and then more pressure being applied the spring arms are spread sufficiently to enable the supplemental head to be carried up until its upper rounded end 14" engages the seat 15 and the shoulders 28 engage the top of the main head. The supplemental head can be readily and quickly arranged in place and removed, as required, and it immediately adapts the machine for filling bottles of a different size. For filling splits a longer supplemental head would be provided and in this way a single machine may be quickly adapted to fill bottles of many different heights.

The valve mechanism which is selected to illustrate the application and use of my present invention is one which I have employed on a machine for filling beer and a bushing 30 having a tapered bore is provided in the filling tube to restrict the flow of beer and permit an expansion thereof in the filling tube, thereby to reduce the pressure and avoid foaming. The invention may be also employed with other valve mechanisms, such, for example, as that described and claimed in Patent No. 768962 dated Aug. 110

30, 1904 in which the flow of air from the bottle during the filling operation is regulated and controlled to prevent the beer from foaming. The invention could also 5 be used with a valve mechanism of the kind described in said patent and having the filling tube provided with a bushing as described in my application No. 313,146 filed concurrently herewith. The machine in 10 which these valve mechanisms are used and for which my present invention is adapted comprises lifting mechanism of suitable character for carrying the bottle up on the filling tube and against the head, or the supplemental head, and then carrying the bottle 15 and head up to first open the air valve 21 and permit an equalization of pressure in the bottle and in the tank or head of the filling machine until finally the head engages 20 the nuts 13 and lifts the rods 11 and cross piece 10 to unseat the liquid valve 9. The pressure of the bottle against the supplemental head will not only seal the bottle but will also force the supplemental head 25 tightly against the seat 15 on the main head and make an effective seal there, although the spring arms may be constructed to hold the supplemental head so tightly against the

seat 15 as to make a very effective seal for all ordinary purposes.

30

What I claim and desire to secure by Letters Patent is:

In a bottle filling mechanism, the combination of a body adapted to be secured to a liquid tank, a filling tube depending from 35 the body, a main head movable on said filling tube, a seat for the bottle at the bottom of the main head, a supplemental head adapted to be arranged on the filling tube to engage said seat and movable with the 40 main head when so engaged, said supplemental head having a seat for the bottle at the bottom thereof, and both of said heads having air passages therein and adapted to communicate with each other, and spring 45 arms on the supplemental head projecting upwardly therefrom, said arms having shoulders adjacent to their upper ends to engage the top of the main head whereby said supplemental head may be held on said 50 main head.

CHARLES L. BASTIAN.
